Jhos d Lockwood

UNITED STATES PATENT OFFICE.

ALEXANDER BERNSTEIN, OF BOSTON, MASSACHUSETTS.

INCANDESCENT ELECTRIC LAMP.

SPECIFICATION forming part of Letters Patent No. 280,340, dated July 3, 1883.

Application filed February 5, 1883. (No model.)

To all whom it may concern:

Be it known that I, ALEX. BERNSTEIN, of Boston, in the county of Suffolk and State of Massachusetts, have invented certain Improvements in Incandescent Electric Lamps, of which the following is a specification.

My invention relates to that class of electric lamps in which the light is produced by the incandescence of a light-giving conductor 5 10 15 closed in a glass globe; and it more particularly concerns the construction of devices by which the said conductors are united to the wires leading into the bulb or globe of the lamp.

In Letters Patent issued to me, dated January 30, 1883, I have shown and described an 15 20 25 30 35 electric lamp in which a hollow or tubular carbon is used as the light-giving conductor. I have therein stated that the said tubular carbon is supported at each end in carbon sockets, to which the conducting-wires leading into and out of the lamp are attached. Experience has demonstrated that a junction, perfect both electrically and mechanically, between the carbon socket and the light-giving carbon and between the socket and the leading-in wires or conductors is a matter of great importance, and is, in fact, essential to the proper working of the lamp. I have accordingly devised an improved method by which the junction may be made. It is self-evident that a mere fitting of the hollow carbon into the socket would not answer, as in that case arcing and disintegration of the carbon would soon take place. A 40 45 50 55 perfect contact is equally requisite between the socket and the conducting-wires to prevent undue heating and melting of the wires, which a defective contact would produce.

In Figure 1 a section of the carbon socket 40 45 50 55 A is shown, and the said socket, exteriorly, may be of any desired shape or configuration. A cylindrical hole, a, is bored in the upper part of the socket, and this hole is made slightly larger than the outside diameter of the light-giving carbon. A smaller cylindrical hole, b, is then bored a short distance into the other end or bottom part of the socket, this hole being just large enough to let the necessary conducting-wire pass through. The space c between the two holes a and b is bored out taper-

ing, as indicated. Fig. 5 is a sectional view on line x x, Fig. 1. The socket being now prepared, the conducting-wire is first joined thereto. This wire B is shown in Fig. 2, its upper end being in the form of an inverted cone, d, which fits the taper hole c in the socket. Before inserting the conducting-wire in place, a mixture of powdered or pulverized carbon with sirup, gum, or similar substance which will carbonize on being heated is 55 60 65 70 75 80 85 90 95 dropped into the socket in order to fill any space which may be left between the socket and that part of the leading-in wire which rests therein. The wire B and socket A, when united, have the form shown in Fig. 3, that part of the figure representing the socket being still shown in section. The next operation consists in putting one of the sockets thus prepared on each end of the hollow carbon cylinder. I employ at this stage of the manufacture the same mixture of powdered carbon and gum, sirup, or similar substance which I have hereinbefore referred to, and in this case, as in the former operation, I may, if I prefer, dispense with the use of powdered carbon, by merely using sirups, or any carbonaceous cement of like nature which carbonizes when heated. After both ends of the hollow carbon are provided, as described, with sockets, the whole presents the appearance shown in Fig. 4, in which A A are sockets; B B, the leading-wires cemented therein, and C the light-giving part inserted in the holes a. The various component parts, being thus put together, are now placed in a suitable furnace, and heated until the gum, sirup, or other carbonaceous cement which has been employed at the several junctions is fully carbonized, after which the electrical and mechanical connection between the different parts is perfect, the whole forming a 90 95 continuous and homogeneous conductor from one end to the other. The pieces, when put together, as in Fig. 4, form a separate article of manufacture, which may be used in incandescent lamps in various ways, as I shall show 100 in future applications. Instead of using a ready-made socket, I may, if I prefer, form such a one around the tubular carbon by applying thereto successive layers of powdered carbon with gum or sirup, and carbonizing

one layer after another, the conducting-wires being introduced between the several layers; but this is an inferior method, generally speaking, and will only be adopted in special cases.

5 Having now fully described my said invention and the manner in which the same is to be carried into effect, I would observe, in conclusion, that although I have described a method of connecting tubular light-giving carbons with sockets and connecting-wires, I make no claim herein thereto, but reserve the same for a separate application.

I claim—

The combination, substantially as hereinbefore described, in an incandescent electric lamp, of a light-giving hollow carbon cylinder, and conical-headed conducting-wires therefor, with supporting-sockets of carbon

placed at each end of the hollow cylindrical carbon, and between the same and the conducting-wires, the said sockets being bored out on one side thereof to fit the ends of the said cylinder, and on the other side with a smaller hole to fit the conducting-wires, and the two holes united by a countersunk hole tapering 25 to the smaller hole, and adapted to fit the conical head of the conducting-wires, for the purposes set forth.

In testimony whereof I have signed my name to this specification, in the presence of two subscribing witnesses, this 1st day of February, 1883.

ALEX. BERNSTEIN.
